UNITED STATES PATENT OFFICE.

CHARLES W. HORN, OF CHICAGO, ILLINOIS.

ROTARY HYDROCARBON EXPLOSIVE-ENGINE.

1,138,566.

Specification of Letters Patent.

Patented May 4, 1915.

Application filed November 13, 1911. Serial No. 659,921.

To all whom it may concern:

Be it known that I, CHARLES W. HORN, a citizen of the United States, and a resident of the city of Chicago, in the county of Cook and State of Illinois, have invented certain new and useful Improvements in Rotary Hydrocarbon Explosive-Engines; and I do hereby declare that the following is a full, clear, and exact description of the same.

10 The object of this invention is to provide certain improvements in rotary hydrocarbon explosive engines, as will be hereinafter more definitely pointed out and claimed, reference being had to the accompanying drawings, in

15 which—

Figure 1 is a top plan view of a device embodying my invention, and illustrating a slightly different valve and transfer construction. Fig. 2 is an end elevation thereof. Fig. 3 is a section taken on line 3—3 of Fig. 1. Fig. 4 is a section on line 4—4 of Fig. 1. Fig. 5 is an enlarged, fragmentary section taken on line 5—5 of Fig. 3, and illustrates the construction and arrangement of 25 the transfer valves. Fig. 6 is a fragmentary section on line 6—6 of Fig. 5. Fig. 7 is a fragmentary section on line 7—7 of Fig. 5. Fig. 8 is a fragmentary section on line 8—8 of Fig. 2. Fig. 9 is a top plan view, partly 30 broken away, of the plunger abutment, showing the same removed from the machine. Fig. 10 is an inner face view thereof. Fig. 11 is a view in end elevation illustrating a slightly modified valve action. Fig. 12 is a 35 side elevation thereof. Fig. 13 is a fragmentary sectional view illustrating the valve action illustrated in Figs. 11 and 12. Fig. 14 is a section taken on line 14—14 of Fig. 13. Fig. 15 is a section taken on line 15—15 of 40 Fig. 14. Fig. 16 is a section on line 16—16 of Fig. 13.

In the construction illustrated in Figs. 1 to 10 inclusive, the power cylinders 40, are arranged side by side upon a suitable base 41, and the main shaft 4, passes therethrough and is provided therein with power elements or heads 42, having oppositely directed power pistons 43, as shown in Fig. 14. In this construction the respective pistons 50 on the power heads for half their travel act as compressing pistons. For this purpose, as shown, an inlet pipe 44, is connected near the bottom of the power cylinder on the inlet side thereof. Slidable through suitable slide apertures in the wall of the cylinder, are plungers 45 and 46, one in advance

of ignition position and the other beyond exhaust position. A relatively small compression chamber 46*, is provided in said power cylinder adjacent the plunger 45, 60 and opening therefrom through a puppet valve 45*, is a passage 47, which leads upwardly around the plunger 45, to an ignition chamber 48, just above said plunger. A spring pressed slide valve 49, holds said 65 passage normally closed to the ignition chamber, as shown in Fig. 5, the stem 50, of said valve for that purpose extending upwardly through the wall of the valve chamber, as shown in Fig. 5, and having 70 a head 51, thereon, and engaged on said stem beneath the head, and bearing on the top of the valve chamber, is a pushing spring 52, which acts to hold said valve closure normally elevated and the passage closed. 75 A spark plug or other ignition means 53, is secured in said ignition chamber. Means are provided for reciprocating said plungers 45 and 46, to permit the passage of the power pistons beneath the same, and to 80 immediately return the same to closed position after the passage of the pistons therebeneath. For this purpose, as shown, powerful pulling springs 54 are secured on the opposite ends of a rod 55, which extend 85 through the outwardly directed arms 56, of each of said plungers and the inner ends of said springs are rigidly secured on any suitable support, for example, the heads of the power cylinders, so that said plungers 90 are normally held by said springs inwardly or in full bearing against the power head, as shown in Fig. 4. Journaled on said rod or shaft 55, is a roller 57, and journaled upon a shaft 58, secured on said frame below the 95 plunger adjacent inlet position and above the plunger at the exhaust position, is a puppet arm 59, which projects into the space respectively between the roller 57, and the plunger. Rigidly secured on said shaft is a 100 crank arm 60, having a roller 61, at its outer end, which tracks upon a cam wheel 62, having throws 63, thereon on diametrically opposite sides thereof, and positioned to simultaneously shift said levers 60, outwardly, 105 thereby moving the plungers outwardly against the tension of their springs. Said throws 63, on said cam wheels are arranged very slightly in advance of the pistons 43, on the power heads 42, so that said plungers are 110 shifted outwardly just as said pistons reach the same to permit the pistons to pass thore-

under, and the throws 63, on said cam having passed the levers 60, simultaneously with the outward movement of said plungers and the passage of the pistons therebeneath, the 5 springs 54, immediately act to pull said plungers inwardly, closing the cylinders behind the pistons. It is just at this moment that the charge is admitted between the piston and the plunger 45. For this purpose, 10 a tappet arm or actuating lever 64, is rigidly secured on a shaft 65, journaled on the frame, and extends over the stem 50, as shown in Fig. 11, engaging the head 51, thereof to shift the valve closure downwardly. A lever or arm 66, is rigidly connected to the tappet arm and extends rearwardly above a cam wheel 67, provided with oppositely disposed throws 68. The throws on said cam wheels are so positioned with 15 reference to the throws on the cam wheels 62, for actuating the plungers, (or the length of said levers are so proportioned, as preferred) to permit said inlet valves to be opened only when the plunger has 20 turned to position behind the power abutment, and the engine is timed for ignition to take place after said valve 49, has again closed under the impulse of its spring 52. An exhaust chamber 69, is provided just 25 above the exhaust abutment 46. This may be opened to the atmosphere through a suitable exhaust pipe 70, or may be controlled, if desired, by a puppet valve 71, either mechanically or automatically actuated.

30 Where a double engine is constructed, as described, the power pistons (and, of course, the corresponding cams and throws thereon for each of the cylinders) are preferably arranged symmetrically, so that the pistons 40 of one cylinder being arranged ninety degrees from those on another, four explosions occur in each rotation of the main shaft. In this construction, the charge is drawn into the cylinder through the inlet pipe 44, 45 and that drawn in by the reduction of pressure caused by one piston is compressed by the next succeeding piston against the plunger 45. As compression augments, the puppet valve 45*, permits a part of the charge 50 to pass into the passage 47, so that the charge under high compression, is contained in said passage 47, when the plungers are retracted. As the piston passes beyond the plunger 45, the same immediately, on an impulse of its 55 spring, falls inwardly into the head, and simultaneously the valve 49, is actuated to permit the charge under full compression, to pass into the spaces between said piston and the plunger. At this moment, ignition 60 occurs behind the piston, such ignition occurring either just before the closing of the valve 49, or just after, depending upon whether it is desired to get the somewhat more continuous effect of the combustion of 65 the gas of the mixture in the passage 47,

or to obtain the impulse afforded only by the ignition of the compressed charge in the explosion or ignition chamber in the power cylinder. The impulse afforded by the explosion is largely expended at the time 70 said piston reaches the plunger 46, which is immediately retracted from before the same simultaneously with the retraction of the plunger 45, to retain a new charge, and the next succeeding piston is positioned in 75 ignition position and the charge having been ignited, the products of combustion for the previous charge are expelled by said piston being forced into the exhaust chamber 69, and thence escaping to the atmosphere 80 through the exhaust pipe.

The construction illustrated in Figs. 11 to 16 inclusive, is the same as that before described, except that the charge is compressed into a cylinder 72, which communicates in a passage 73, corresponding with the passage 47, before described, and in which is a valve 49, as before described. A piston 74, is provided in said cylinder and the connecting rod 75, thereof, is engaged 90 upon a wrist pin 76, set in a relatively small gear 77, driven from a gear 78, of twice the periphery (affording a two to one drive) and secured on the main shaft 4. Said gears are so set and timed as to throw the piston 95 outwardly to full compression the moment the plungers close behind the respective pistons, thus greatly augmenting the compression of the charge in the ignition chamber. As shown in Fig. 14, the valve 79, corresponding with the valve 45*, shown in Fig. 5 before described:

Of course, other modifications of the arrangement of valves may be effected, if desired, and obviously, numerous other minor 105 modifications will readily suggest themselves as to the arrangement of valves and the particular means for actuating the valves, and I do not purpose limiting the patent granted on this application otherwise than 110 necessitated by the prior art.

I claim as my invention:

1. In a device of the class described, a power cylinder, a power head revoluble therein, fixed and rigid pistons diametrically 115 opposite thereon and fitting in the cylinder, diametrically opposite disposed abutments in said cylinder, means for retracting said abutments with the approach of the power piston and returning the same to position immediately behind said pistons, means for supplying an explosive charge for compression between one of said abutments and one of said pistons, a cam actuated valve permitting a transfer of the mixture to the other 120 sides of said abutment when compressed by the movement of said piston and an igniter in the transfer passage.

2. In a device of the class described, a power cylinder, a power head revoluble 125

therein, fixed and rigid pistons diametrically opposite thereon and fitting in the cylinder, diametrically opposite disposed abutments in said power cylinder, means for retracting said abutments with the approach of the power piston and returning the same to position immediately behind said pistons, means for supplying an explosive charge for compression between one of said abutments and one of said pistons, a compression cylinder and piston auxiliary to said power pistons for augmenting the compression of said charge when delivered thereto, a cam ac-

tuated valve permitting a transfer of mixture to the other side of said abutment when further compressed by said auxiliary cylinder and piston and an igniter in the passage between the compression cylinder and the power cylinder.

In testimony whereof I have hereunto subscribed my name in the presence of two subscribing witnesses.
